UNITED STATES PATENT OFFICE.

WILLIAM BLACKMORE, OF CLEVELAND, OHIO, ASSIGNOR TO THE NATIONAL MALLEABLE CASTINGS COMPANY, OF CLEVELAND, OHIO.

COUPLING-SUPPORT.

1,293,675.

Specification of Letters Patent. Patented Feb. 11, 1919.

Application filed December 31, 1914. Serial No. 879,816.

To all whom it may concern:

Be it known that I, WILLIAM BLACKMORE, a citizen of the United States, residing at Cleveland, Cuyahoga county, Ohio, have invented new and useful Improvements in Coupling-Supports, of which the following is a specification, reference being had to the accompanying drawings, in which:

Figure 1 is a side elevation partly in section, showing my improved coupler support applied to a car coupler; Fig. 2 shows a front elevation of the coupler support, the coupler being in section; Fig. 3 is a section on lines III—III of Fig. 2; Fig. 4 shows an elevation of a modified form of my device; Fig. 5 is a section thereof, on lines V—V of Fig. 4; Fig. 6 is a front elevation of a further modification; and Fig. 7 is a section on lines VII—VII of Fig. 6.

My invention relates to coupler supports particularly adapted for use with a radial draft gear, and consists in mounting the coupler on a rotatable member, which, in turn, is supported by the carry iron. My invention also consists in the construction and coöperation of the various parts which I shall hereinafter describe and claim.

Referring to the drawings, 2 represents the carry iron bolted or otherwise secured to the end sills 3 of the car. The central portion of the carry iron 2 is provided with a downwardly extending recess or pocket 4, which is arc-shaped laterally, its center of curvature being coincident with the pivotal point of the draft gear. The rocker 5, the lower face 6 of which is arc-shaped, with reference to its rounded upper end or hub 7, has a bearing upon the track 8, which comprises the bottom of the pocket 4. The rocker 5 is also curved laterally to coincide with the curvature of the pocket 4. The lower face 6 of the rocker 5 has a plurality of teeth 9, preferably of less width than the face 6, which engage apertures 10 in the bottom of the pocket 4. The hub 7 of the rocker 5 engages a socket 11 in a bearing block or supporting plate 12. In the block 12 are rollers 13, having axes at right angles to the longitudinal center line of the coupler, the ends of which are of less diameter than their central portion, and are journaled in bearings 14 in the upper face of the plate 12. The housing 15, within which the coupler shank 16 is contained, is supported directly

upon the rollers 13, which permit longitudinal movement of the housing and coupler shank, with a minimum amount of friction. The ends 17 of the block 12 are turned upwardly about the lower side faces of the housing 15, so that lateral movement of the housing will carry with it the block 12 and the rocker 5. As the coupler moves laterally, carrying with it the block 12, the rocker 5 will roll along the track 8 of the pocket 4, and, because of the engagement of the teeth 9 in the corresponding apertures 10 in the pocket 4, the rocker 5 will always be returned to central position. The engagement of the teeth 9 with the apertures 10 will maintain the rocker in its proper position in the pocket 4, and will also prevent the rocker from sliding along the track 8, or from becoming wedged in the pocket.

When the coupler moves longitudinally, under buffing or pulling stresses, the housing 15 is carried by the rollers 13 in the bearing block 12, which is held from longitudinal movement by its engagement with the rocker 5, which, in turn, is held from longitudinal movement by its teeth 9, and the vertically extending walls of the pocket 4.

In Figs. 4 and 5 I have shown a modification of my invention, in which I employ two rockers 5', which tend to give the coupler greater resistance to twisting, the rockers 5' being arranged one on each side of the longitudinal axis of the coupler, and being mounted in pockets 4' on the carry iron 2', the centers of curvature of which are coincident with the pivotal point of the draft gear.

In Figs. 6 and 7 I have shown a further modification of my invention, in which the bearing plate or block is eliminated, and the connection between the housing 15² and the rocker 5² acts as a ball and socket joint 18. The socket is integral with the housing 15², so that, as the coupler moves longitudinally, the upper portion of the rocker 5² is carried with it, and the rocker is tipped either forwardly or rearwardly. The rim or periphery 6² of the rocker 5² is rounded in transverse section, to provide a socketed bearing in the floor of the recess 4², and the apertures 10² are flared downwardly and outwardly to permit the tilting movement. In the lateral movement of the coupler the rocker 5² operates as in the preferred form, but in the longitudi-

nal movement the rocker acts as a link pivoted in the socket 18, and in the apertures 10² of the pocket 4².

It is obvious that various modifications 5 may be made in the constructions which I have shown and described herein, without departing from my invention.

What I claim is:

1. In coupler supports, a draft member in 10 combination with a laterally-movable rocker and a guideway therefor, a member intermediate the rocker and the draft member having an engagement with the rocker, and an anti-friction bearing on the draft member, 15 said draft member being moved relatively to the intermediate member on said anti-friction bearing and movable with the intermediate member laterally on said rocker.

2. In coupler supports, a coupler having a 20 shank mounted for both longitudinal and lateral movement in a horizontal plane, a support for said shank, and a plurality of anti-frictional means mounted between said

shank and said support, one of said means permitting said shank to have substantially 25 non-frictional movement laterally in a horizontal plane, and the other of said means permitting said shank to have substantially non-frictional movement longitudinally in a horizontal plane.

3. In coupler supports, a coupler having a shank mounted for both longitudinal and lateral movement, a support for said shank, an intermediate laterally-movable member, a roller device mounted between said intermediate member and said shank, and a second roller device mounted between said intermediate member and the support, whereby said coupler is permitted to have a substantially non-frictional movement both 30 35 longitudinally and laterally.

WILLIAM BLACKMORE.
